UNITED STATES PATENT OFFICE

146,817

DESIGN FOR A SUIT

Jane Walker, New York, N. Y.

Application November 20, 1946, Serial No. 134,918

Term of patent 3½ years

(Cl. D3—4)

To all whom it may concern:

Be it known that I, Jane Walker, a citizen of the United States, residing in New York city, in the county of New York and State of New York, have invented a new, original, and ornamental Design for a Suit, of which the following is a specification, reference being had to the accompanying drawing, forming part thereof.

Fig. 1 is a front view of a suit, showing my design,

Fig. 2 is the rear view of the suit shown in Fig. 1, and

Fig. 3 is a fragmentary front view of the skirt member on a reduced scale, illustrating the waist and pockets thereof.

I claim:

The ornamental design for a suit, substantially as shown and described.

JANE WALKER.
